UNITED STATES PATENT OFFICE.

CHARLES E. WHITMAN, OF ST. LOUIS, MISSOURI.

BALING-PRESS.

SPECIFICATION forming part of Letters Patent No. 485,072, dated October 25, 1892.

Application filed April 22, 1892. Serial No. 430,258. (No model.)

To all whom it may concern:

Be it known that I, CHARLES E. WHITMAN, of the city of St. Louis, in the State of Missouri, have invented a certain new and useful Improvement in Baling-Presses, of which the following is a full, clear, and exact description, reference being had to the accompanying drawings, forming part of this specification.

10 My invention relates to certain improvements in presses of the continuous type for baling hay, straw, excelsior, and the like; and my invention consists in features of novelty hereinafter fully described, and pointed 15 out in the claims.

Figure I is a top view of the power end of my improved press. Fig. II is a side elevation of same. Fig. III is a section taken on line III III, Fig. IV. Fig. IV is a section 20 taken on line IV IV, Fig. III. Fig. V represents a modification of the construction shown in Figs. III and IV. Fig. VI is an enlarged top view of the power-head. Fig. VII is a top view of the central portion of the 25 press, and Fig. VIII is an elevation of same.

Referring to the drawings, 1 represents a beam connecting the baling-chamber 2 to the power portion of the press.

3 is the sweep, and 4 the power-head, mounted on a shaft or heavy rod 5. The sweep and head are connected in any suitable manner, so as to turn together on the shaft or rod 5.

6 is the pitman, secured to the plunger 7, as usual, and its outer end is formed with an 35 inner shoulder 8 and an outer shoulder 9.

The power-head 4 is peculiar in its construction. (See Fig. VI.) It has two outer bearing-points 10, preferably armed with rollers 11, and two inner bearing-points 12, 40 preferably armed with rollers 13. In the operation of the press as the power-head is moved by the sweep one of the points 10 comes against the shoulder 8 of the pitman, forcing the pitman and plunger forward with a rapid 45 movement. Just before the point 10 leaves the shoulder 8 one of the points 12 comes against the shoulder 9 of the pitman and completes the movement of the plunger with a slow and powerful pressure, and just before 50 the pitman is brought into line with the center of motion of the power-head its extreme end 15 comes in contact with the power-head

at about the point marked *a*, which causes the pitman to be disengaged from the power-head, permitting the plunger to recede under 55 the back expansion of the compressed material, which may be assisted by a spring 17, the pitman returning on the same side of the press, and in its backward movement all danger of its striking the points 10 is prevented 60 by projections or corners 18 on the power-head, which will ward the pitman off from the bearing-points 10. The further movement in the same direction of the sweep and cross-head will bring the next points 10 and 65 12 into engagement with their shoulders 8 and 9 on the pitman, and the action described is repeated, one revolution of the sweep effecting two forward movements of the plunger. 70

The device is an exceedingly strong, cheap, and durable one, as well as very effective, as has been found by practical tests.

Should the plunger and pitman fail to return to the limit of their backward movement 75 there might be danger of the bearing-points 10 engaging the shoulder 9 of the pitman, and to avoid any danger of this kind I put a cam 19 on the end of the pitman, (this cam is out of the path of the bearing-points 12,) against 80 which the parts *b* of the power-head will strike, and by forcing the pitman laterally will prevent the bearing-points 10 from engaging the shoulder 9. To permit this lateral movement, of the pitman at such times, I employ a device which in its preferred form consists of an arm 21, pivoted to the pitman at 22 and connected at its other end (see Figs. I, III, and IV) to a block 23, mounted on a rod 24, one end of which is secured by a bracket 25 90 to the beam 1. The other end of the rod fits in a slot 26 of a casting 27, secured to the beam 1, the casting having a socket 28, in which fits a spring 29, that tends to hold the rod 24 away from the pitman 6. The block 95 23 is held against the casting 27 (or against a washer 30, which bears against the casting 27) by means of a spiral spring 31, surrounding the rod 24, this spring permitting a slight movement of the block on the rod when necessary. It will thus be seen that should the part *b* come against the cam 29 the outer end of the pitman will be forced laterally and will then be drawn back to its normal position by 100

the spring 29, acting through the rod 24, block 23, and arm 21.

In Fig. V, I have shown a modification of the spring 29, which consists in forming the

5 arm 21 in two parts, one of the parts having a socket 32 to receive the end of the other part and a spring 33, the part of the arm fitting in the socket having a head 34, between which and a nut 35 on the socket part 10 of the arm the spring 33 bears. In this construction the spring 33 will yield to the lateral movement of the pitman and will draw the pitman back to its normal position.

The plunger 7 of the press is provided with 15 a stop extension 40, to which a leaf 41 is hinged at 42. The extension 40 is pivoted to the plunger, as shown at 43, so that it will move freely in the frame of the press and so that any twisting of the plunger will not be 20 transmitted to the extension or to the leaf 41. The leaf 41 has cam-shaped sides 44, which as the plunger is forced into the press come against cleats 45, secured to the inner wall of the baling-chamber, as shown in Fig. VIII 25 and by dotted lines in Fig. VII. It will thus be seen that as the plunger is forced inwardly the leaf 41 will be raised up into a horizontal position and will close the mouth of the hopper 46 while the plunger is in its forward position, thus avoiding the possibility of material entering the baling-chamber behind the plunger. Then as the plunger recedes the leaf 41 will drop down into the position shown in Fig. VIII, thus shortening up the press and 30 permitting the draft-animals to step over the beam and pitman close up to the baling-chamber of the press.

47 represents a roller, upon which the outer end of the pitman rides and is supported from 40 vertical movement.

I claim as my invention—

1. In a full-circle baling-press, the combination of a baling-chamber, a plunger, a pitman having a cam and a plurality of shoulders on its outer end, a sweep, and a power-head having means to engage said cam and having a plurality of bearing-points on each side of its center, which are arranged to successively engage the shoulders of the pitman, 45 said cam being out of the line of movement of said bearing-points, substantially as and 50 for the purpose set forth.

2. In a full-circle baling-press, the combination of a baling-chamber, a plunger, a pitman having an inner and an outer shoulder and a point 15, a sweep, and a power-head,

said power-head having an inner and an outer bearing-point on each side of its center and having surfaces *a* and projections 18, substantially as and for the purpose set forth. 60

3. In a full-circle baling-press, the combination of a baling-chamber, a plunger, a pitman having an inner and an outer shoulder, a cam secured to the pitman at the outer shoulder, a sweep, and a power-head, said 65 power-head having an inner and outer bearing-point on each side of its center and having a part *b* for engaging said cam of the pitman, substantially as and for the purpose set forth. 70

4. In a full-circle baling-press, the combination of the baling-chamber, a plunger, a pitman having an inner and outer shoulder, and a cam on the pitman secured thereto at the outer shoulder, a spring-actuated arm connecting 75 the pitman to the frame of the press, a sweep, and a power-head, said power-head having an inner and outer bearing-point on each side of its center and having a part *b* for engaging said cam, substantially as and for the purpose set forth. 80

5. In a full-circle baling-press, the combination of a baling-chamber, a plunger, a pitman having an inner and outer shoulder, and a cam located at the outer shoulder, an arm pivoted to the pitman, a spring-actuated rod to 85 which the arm is connected, a sweep, and a power-head having inner and outer bearing-points on each side of its center, and a part *b* for engaging said cam, substantially as and 90 for the purpose set forth.

6. In a full-circle baling-press, the combination of a baling-chamber, a plunger, a pitman having an inner and outer shoulder, an arm pivoted to the pitman at one end, a 95 rod upon which the other end of said arm is mounted, a spring 31, located on said rod, a sweep, and a power-head having inner and outer bearing-points for engaging the shoulders on the pitman, substantially as and for 100 the purpose set forth.

7. In a baling-press, the combination of a baling-chamber, a plunger, means for moving the plunger, an extension pivoted to the plunger, a leaf hinged to the extension and 105 provided with cam-shaped sides, and cleats against which the cams of the leaf impinge, substantially as and for the purpose set forth.

CHARLES E. WHITMAN.
